US0D1027850S

(12) **United States Design Patent** (10) **Patent No.:** **US D1,027,850 S**
(45) **Date of Patent:** **** May 21, 2024**

(54) **CHARGER**

(71) Applicant: **Guangdong Juchong Tianxia electronics Co., LTD**, Shenzhen (CN)

(72) Inventor: **Caiyun Gao**, Zhangzhou (CN)

(73) Assignee: **Guangdong Juchong Tianxia electronics Co., LTD**, Shenzhen (CN)

(**) Term: **15 Years**

(21) Appl. No.: **29/929,582**

(22) Filed: **Feb. 22, 2024**

(51) LOC (14) Cl. **13-02**

(52) U.S. Cl.

USPC **D13/107**

(58) **Field of Classification Search**

USPC D13/103, 107, 108, 118, 119, 184, 199;

(57) **CLAIM**

The ornamental design for a charger, as shown and described.

DESCRIPTION

FIG. 1 is a top perspective view of a first embodiment of a charger, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of a second embodiment thereof;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom thereof;

FIG. 17 is a top perspective view of a third embodiment thereof;

FIG. 18 is a bottom perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof; and,

FIG. 24 is a bottom view thereof.

The broken lines in the drawings illustrate the portions of the charger, which form no part of the claimed design.

1 Claim, 24 Drawing Sheets
